Specification for Design.

Patented May 8, 1917.

Application filed February 7, 1917. Serial No. 147,261. Term of patent 14 years.

To all whom it may concern:

Be it known that I, WILLIAM C. PAUL, a citizen of the United States, residing in the city of Newark, in the county of Essex and State of New Jersey, have invented a new, original, and ornamental Design for a Non-Glare Lamp-Casing, of which the following is a specification, reference being had to the accompanying drawings, forming a part thereof.

In the drawings,

Figure 1 represents a front elevation of a

non-glare lamp casing, illustrating my new design; and

Fig. 2 represents a side elevation of the same.

I claim:

The ornamental design for a non-glare lamp casing, as shown.

WILLIAM C. PAUL.
